Atty.

UNITED STATES PATENT OFFICE.

JOHN W. HUFF, OF FLAGSTAFF, ARIZONA.

CAR-STAKE.

1,358,154.

Specification of Letters Patent. Patented Nov. 9, 1920.

Application filed June 10, 1920. Serial No. 337,825.

To all whom it may concern:

Be it known that I, JOHN W. HUFF, a citizen of the United States of America, residing at Flagstaff, in the county of Coconino and State of Arizona, have invented

5 certain new and useful Improvements in Car-Stakes, of which the following is a specification.

10 My invention relates to car stakes and more particularly to that type of stake that is used on logging car bunks.

15 One of the objects of my invention is the provision of an improved car stake as above specified of the rotating type.

20 Another object of my invention is to provide a stake which has associated therewith a combination of parts that retain the stake in a positive locked position while bearing a load and that will surely and effectively 25 release the stake from that position when so desired.

25 A still further object of my invention is the production of a device of the kind above described that after release of the load can be returned to a load bearing or locked position with the minimum effort in the minimum time.

30 With these and other objects in view, my invention consists of features of construction, combination and arrangement of parts hereinafter fully described and claimed.

In the accompanying drawings

35 Figure 1 is a front elevation showing the stake in a load bearing position;

Fig. 2 is a front elevation showing the stake in a released position;

Fig. 3 is an end elevation showing the stake in a load bearing position, and

Fig. 4 is a top plan view of the device 40 showing the stake in a load bearing position.

45 Referring more particularly to the drawings wherein like characters represent like parts in all views, 10 designates a bolster which carries the transverse bunks, in this instance parallel rail sections 11 and 11' secured by any suitable means. As clearly shown these rails extend beyond the end of the bolster 10 and in that extending portion 50 of the rails is carried a pin 12 which in turn has pivotally mounted thereon the stake 13. The lower end of the stake 13 is bifurcated to provide spaced legs 14 in each of which is formed an elongated opening 15 that receives the pin 12 to pivotally connect the stake to the rails 11 and 11'.

If so desired the pin 12 can be held from movement in the rails by means of cotter pins 16 passing through the same adjacent its ends.

60 A strap 17 is secured to one face of the bolster 10 and pivotally carries the locking bar 18, the said bar extending across the end face of the bolster and the free end thereof projecting beyond the opposite side 65 of the bolster from that on which the strap 17 is positioned. To insure the pivotal connection of the bar 18 with the strap 17 a head 19 is formed on the outer end of the strap. The downward movement of the 70 bar 18 is limited by its engagement with the bracket 20 which is mounted on the end face of bolster. As is clearly shown in Figs. 1 and 3 the lock bar 18, when in a raised position, is adapted to engage the legs 14 75 of the stake to prevent the same from swinging outwardly, the inward movement of the stake being limited by its engagement with the enlargement 21 on the strip 22 that is carried by the rail 11'.

80 I have provided a very simple and efficient means for releasably retaining the lock bar in a raised position and thus hold the stake in a load bearing position. The description of this means will now ensue. A 85 trip lock block 23 is pivoted to the bolster, the same comprising a body 24 having a grip 25 extending from one side thereof and an arm 26 projecting from the opposite side.

80 The trip block is so pivoted to the bolster as to fall by gravity to the position as shown in Fig. 2. To retain the trip lock block 23 in engagement with the lock bar 18 a rectangular locking block 27 is pivoted to the bolster adjacent the trip block 23 and capable of engaging the arm 26 of the trip block when the latter is holding the bar 18 95 in a raised position in engagement with the stake. Because the lock block 27 is pivoted off center it, when allowed movement, seeks to attain a horizontal position with the greater mass thereof below the point of pivot. By so doing the lock block 27 is always urged by gravity against the trip block 23 or the arm 26 thereof. It will be 100 noted that when the parts are in a position as shown in Fig. 2 and the stake has been allowed to swing outwardly from a vertical position the same drops down on the pin 12 the length of the elongated opening in 105 each leg 14 of the stake so that no part of the stake will project above the rails 11 110

and 11' to impede the movement of logs over the ends of the rails.

Assuming the parts in the position illustrated in Fig. 2. When it is desired to raise 5 the stake and lock it in a load bearing position, the stake is first moved to a position as shown in Figs. 1 and 3 and the trip block is moved by means of the grip 25 to a vertical position and comes in contact with 10 the free end of the bar 18 on its change from a horizontal to vertical position, moving the free end of the bar 18 to a raised position in engagement with the legs of the stake to prevent the outwardly swinging 15 movement of the same. As the trip block is moved to a vertical position the lock block 27 moves by gravity from a substantially horizontal position, with one end resting on the end of the arm 26, to a vertical 20 position to permit the arm 26 to be positioned beneath one end of the lock block. When in this position, as shown in Figs. 1 and 3 all parts are held immovable. To release the stake the lock block 27 is moved 25 to a horizontal position thus allowing the trip block to move by gravity to a substantially horizontal position and thereby permit the free end of the bar 18 to swing downwardly to release the stake.

From the foregoing description, taken in connection with the drawings, it will be seen that my invention provides a car stake and locking means therefor which is simple in construction and designed to carry out the objects of the invention in a reliable and efficient manner. It will, of course, be understood that while the construction disclosed is the preferred embodiment of my invention, changes may be made within the scope of the appended claim without departing from the spirit of the invention.

What I claim is:

The combination with a support, a stake pivotally carried thereby, a movable lock bar adapted to engage said stake, a pivoted 45 trip block comprising a body having a grip extending from one side edge thereof and adapted to engage beneath and support the lock bar, said trip block having an arm projecting from the opposite side edge, and 50 a pivoted lock block adapted to engage said opposite side of said body of the trip lock block and said arm to retain said trip lock block in a vertical position in engagement with said lock bar.

In testimony whereof I affix my signature.

JOHN W. HUFF.
